UNITED STATES PATENT OFFICE.

HERMAN PRIES, OF MICHIGAN CITY, INDIANA.

BRAKE-SHOE.

949,945.

Specification of Letters Patent. Patented Feb. 22, 1910.

Application filed November 8, 1909. Serial No. 526,867.

To all whom it may concern:

Be it known that I, HERMAN PRIES, a citizen of the United States, and resident of Michigan City, county of Laporte, and State of Indiana, have invented certain new and useful Improvements in Brake-Shoes, of which the following is a specification, and which are illustrated in the accompanying drawings, forming a part thereof.

13. The invention relates to brake shoes for railway cars, its object being to increase the strength of such devices and to improve the character of the wearing faces thereof.

15. It consists of a structure such as is hereinafter described, and is illustrated in the accompanying drawings, in which—

16. Figure 1 is a central longitudinal section of the brake shoe on a plane perpendicular to its face; Fig. 2 is a perspective of the reinforcing plate used in the shoe; and Fig. 3 is a sectional view taken on the line 3—3 of Fig. 1.

17. The brake shoe consists of the body portion 10, usually of gray iron, and the reinforcing plate 11, the former being cast or chilled upon the latter. The novelty resides in the form of the reinforcing plate which is of a tougher and stronger material than the body of the shoe. The plate 11 is so disposed in the mold that its outer face is substantially flush with the back face of the body portion of the brake shoe, and it is provided with the usual outstanding loop 12, by means of which the shoe may be secured in position for service. The plate 11 has a number of instanding lugs, that is to say, lugs which extend toward the wearing face of the shoe. These lugs are provided with lateral projections, preferably adjacent their ends, as shown, which serve the double purpose of increasing the anchorage of the reinforcing plate to the body, and of increasing the area of the chilled zones adjacent the face of the shoe. As shown, there is a pair of such lugs, designated 13, 14, at the middle of the shoe, and shown as continuations of the side walls of the loop 12, such lugs, therefore, extending longitudinally of the shoe and being located one upon each side of its median line. Each of these lugs has at its inner end a lateral projection 15, 16, such projection extending toward the median line of the shoe, thereby leaving space between them to be filled by the molten metal as the body is cast. Two similar sets of lugs 17, 18 and 19, 20, are

located respectively adjacent the two ends of the plate 11, and are transversely disposed with reference thereto. A member of each of these pairs of lugs is provided with lateral projections 21, 22, and 23, 24, at their inner ends and directed toward each other, but, however, being spaced apart.

18. The plate 11 is preferably apertured between the members of each of the three pairs of lugs, as shown at 25, 26, 27, and is recessed at its ends, as shown at 28, 29, thereby providing a considerable mass of gray iron between each pair of the lugs, to constitute a strong key, for locking the two members of 65 the shoe together. The plate 11 and its appurtenances are sufficiently massive to have marked chilling action upon the iron as it is poured into the mold, and the instanding lugs and their lateral projections extend this 70 chilling action over a very considerable portion of the area of the face of the shoe. These lugs, however, are so disposed that portions of the gray iron at the ends of the shoe, and between the several pairs of lugs, 75 come but slightly under the chilling influence, and, as a result, the face of the shoe comprises a plurality of zones each of considerable area, of comparatively hard and soft material, and it is found in practice 80 that the braking action of such a shoe is greatly superior to that of a shoe the face of which is either of substantially uniform density or has comparatively small spots of hardened metal. 90

I claim as my invention:

1. A brake shoe comprising a body portion chilled upon a reinforcing plate of tougher material, such plate having lugs projecting into the body and provided at 95 their ends with lateral extensions.

2. A brake shoe comprising a body portion chilled upon a reinforcing plate of tougher material, such plate having lugs projecting into the body and provided at 100 their ends with lateral extensions, such lugs being arranged in pairs and the lateral extensions of each pair projecting toward each other.

3. A brake shoe comprising a body portion chilled upon a reinforcing plate of tougher material, such plate having lugs projecting into the body and provided at 105 their ends with lateral extensions, such extensions being arranged in pairs, some thereof extending longitudinally and others transversely as to the shoe, the lateral projections 110

of the members of each pair of lugs extending toward each other.

4. A brake shoe comprising a body portion chilled upon a reinforcing plate of
5 tougher material, such plate having lugs
projecting into the body and provided at
their ends with lateral extensions, such lugs
being arranged in pairs and the lateral ex-

tension of each pair projecting toward each other, the reinforcing plate being apertured ¹⁶ between the members of each pair of lugs.

HERMAN PRIES.
